CARL F. DOERR, OF YONKERS, NEW YORK.

ROTARY GLASS CUTTER.

1,421,921.

Specification of Letters Patent.

Patented July 4, 1922.

Application filed April 22, 1921. Serial No. 463,693.

To all whom it may concern:

Be it known that I, CARL F. DOERR, a citizen of the United States, and a resident of Yonkers, in the county of Westchester and State of New York, have invented a new and Improved Rotary Glass Cutter, of which the following is a full, clear, and exact description.

The invention relates to glazier's implements, and its object is to provide a new and improved rotary glass cutter arranged to enable the user to readily adjust the glass cutter for cutting glass disks of any desired diameter.

Another object is to prevent accidental shifting of the base on the glass during the cutting operation and to prevent the binding of the cutter bar.

Another object is to counterbalance the cutter with a view to insure easy running of the revoluble cutter on the glass.

Another object is to permit of quickly replacing worn out or broken cutters by new ones and without requiring the aid of skilled workmen for making the change.

Another object is to permit of using the cutter on flat or convex surfaces and the cutting of smaller circular disks.

With these and other objects in view, the invention consists of certain novel features of construction as hereinafter shown and described and then specifically pointed out in the claims.

A practical embodiment of the invention is represented in the accompanying drawings forming a part of this application, in which similar characters of reference indicate corresponding parts in all the views.

Figure 1 is a plan view of the improved rotary glass cutter;

Figure 2 is a side elevation of the same with the cutter head shown in section;

Figure 3 is a cross section of the improved rotary glass cutter on the line 3—3 of Figure 1;

Figure 4 is a side elevation of the adjustable cutter head; and

Figure 5 is a rear face view of the same.

The base 10 of the improved rotary glass cutter is provided at its under side with a lining 11 of felt or other suitable material adapted to rest on the surface of the glass 12 to be cut into a circular shape, as herein-after more fully explained. The base 10 is provided with an upwardly extending post or pivot 15 on which is mounted to turn hori-

zontally a bearing member 16 resting on the base 10 and held against upward movement by a nut 17 screwing on the reduced upper end 18 of the pivot 15. The pivot 15 forms 60 with its reduced portion 18 a shoulder 19 located a short distance above the top of the bearing member 16 to form an abutment for the nut 17 and thus allow free turning of the bearing member 16 without danger of binding by the nut 17.

The bearing member 16 is provided to one side of the pivot 15 with a transversely extending pivot 25 on which is mounted to swing up and down the head 26 of a cutter 70 carrier 27, preferably in the form of a bar attached to the head 26 by fitting into a socket 28 therein and held in the socket by a set screw or pin 29. The cutter carrier 27 extends from the pivot 15 laterally in one 75 direction, and the head 26 is provided with an integral counterbalancing weight 30 extending in an opposite direction from the said pivot 15. By the arrangement described the cutter carrier 27 is mounted to swing up and 80 down on the bearing member 16 which latter is mounted to turn on the vertical pivot 15.

The nut 17 is preferably concave on the top to form a fingerhold for the operator to press the base 10 in firm contact with the 85 surface of the glass 12 during the cutting operation without interfering with the free rotation of the cutter carrier 27. On the carrier 27 is mounted to slide a sleeve 40 adapted to be fastened in place on the carrier by 90 a set screw 41 or other suitable fastening device. On the sleeve 40 is mounted to turn the hub 42 of a cutter head 43 carrying a plurality of cutters 44 of disk form and having peripheral cutting edges. Each of the 95 cutters 44 extends into a recess 45 formed in the peripheral face of the cutter head 43, and each cutter 44 is mounted to turn on a shaft or axle 46 held removably in an opening 47 formed lengthwise of the cutter head 100 43. Each of the cutters 44 projects a distance beyond the peripheral face of the cutter head 43, as plainly shown in the drawings, and the cutter in lowermost position at the time is the one used for cutting the surface of the glass 12, as plainly shown in Figure 2. The cutters 44 are arranged in a circle, the center of which coincides with the center of the cutter head 43, and the said cutters 44 are spaced equal distances apart, 105 as shown in Figure 5. It is understood that on turning the cutter head 43 on the sleeve 40

any one of the cutters 44 can be moved into lowermost cutting position, and after this adjustment has been made the cutter head 43 is fastened in position on the sleeve 40. 5 For this purpose the hub 42 of the cutter head 43 is provided with notches 48 extending longitudinally and spaced equal distances apart circumferentially in alinement with the corresponding axles or shafts 46 carrying the cutters 44. The sleeve 40 is provided with an upwardly extending screw 50 on which screws a nut 51, and the said screw 50 is adapted to engage any one of the notches 48 after the cutter head 43 has 10 been turned into the desired position with a view to move the corresponding cutter 44 into lowermost position. When this has been done, the nut 51 is screwed down on the screw 50 and against the hub 42 to fasten 15 the cutter head 43 in position on the sleeve 40 with one of the cutters in lowermost active position for cutting the surface of the glass 12. It is understood that the cutter head 43 is shifted longitudinally on the 20 sleeve 40 to engage or disengage the corresponding notch 48 with the screw 50 and at 25 the time the nut 51 is partly unscrewed. When the desired notch 48 is in engagement with the screw 50 then the nut 51 is screwed 30 down to fasten the cutter head 43 to the sleeve 40. It is understood that on moving the sleeve 40 lengthwise on the carrier 27 the cutting edge of the cutter 44 in bottom position at the time is a desired distance from the 35 axis of the pivot 15 to cut the disk a desired size.

In order to aid the glazier or other person using the rotary glass cutter to accurately set the cutter for cutting a disk of the 40 desired diameter the bar forming the carrier 27 is preferably graduated with a linear measurement, as plainly indicated in Figure 1.

From the foregoing it will be seen that by 45 the arrangement described the user of the rotary glass cutter can readily adjust a cutter head 43 to cut a glass disk of any desired diameter. By providing the head 26 of the cutter carrier 27 with a counterbalancing 50 weight 30, the cutter carrier 27 and the cutter head 43 mounted thereon are counterbalanced to permit of readily swinging the cutter carrier around for the lowermost cutter 44 to cut into the glass 12. By mounting the 55 cutter carrier 27 to swing up and down on the bearing member 16 it permits convenient cutting of convex surfaces.

In practice six disk cutters 44 are provided, of which one is used at the time, and 60 when dull the cutter head can be readily adjusted on the sleeve 40 to move another disk cutter 44 into cutting position, and when all the cutters have become dull they can be readily removed from the cutter head 43 and 65 replaced by new ones. To do this it is only

necessary to push the shafts or axles 46 out of the openings 47 to permit removal of the disk cutters 44. New disk cutters can now be inserted in the recess 45 and the axles or shafts 46 replaced to permit of using the 70 cutter head 43, as above described, with the new disk cutters in position.

It will be noticed that bar carriers 27 of different length may be used for cutting disks varying considerably in diameter, thus 75 for disks, say of six inches and less, a corresponding bar is used, and for cutting disks of more than six inches in diameter a longer bar is used.

Having thus described my invention, I 80 claim as new and desire to secure by Letters Patent:

1. In a rotary glass cutter, a cutter bar, a sleeve adjustably fastened to the said cutter bar, a cutter head provided with cutters arranged in spaced relation and projecting from the peripheral face of the cutter head, the latter being mounted to turn on and to slide on the said sleeve to allow of adjusting the cutter head on the sleeve, and means securing the adjusted cutter head in place on the sleeve. 85

2. In a rotary glass cutter, a cutter bar, a sleeve slidable on the said cutter bar, a cutter head having a hub mounted to turn on and to slide on the sleeve, the hub having notches, a clamping screw on the said sleeve and adapted to engage any one of the said hub notches, and cutters held on the said cutter head and projecting from the peripheral 90 face thereof in spaced relation and relative to the said notches to allow of adjusting the cutter head with any one of the cutters in lowermost cutting position. 95

3. A rotary glass cutter, comprising a base having a vertical pivot, a member mounted to turn on the said pivot and extending laterally therefrom in one direction, a cutter bar extending laterally from the said pivot in an opposite direction and having a head pivoted 110 on the said member to swing up and down, a cutter head carrying a plurality of cutters, and a sleeve held lengthwise adjustible on the said bar and on which the said cutter head is adjustably mounted to permit of moving any one of the cutters into cutting position. 115

4. A rotary glass cutter, comprising a base having a vertical pivot, a member mounted to turn on the said pivot and extending laterally therefrom in one direction, a cutter bar extending laterally from the said pivot in an opposite direction and having a head pivoted on the said member to swing up and 120 down, a cutter head having recesses in its 125 peripheral face and having a hub provided with notches, disk cutters in the said recesses and projecting from the peripheral face of the cutter head, pivots held in the cutter head and on which the said disk cutters are 130

mounted to turn, a sleeve slidably mounted on the said bar, a clamping means on the said sleeve and adapted to engage any one of the notches on the hub of the said cutter 5 head, and a fastening means fastening the said sleeve to the said bar.

5. A portable device for cutting glass disks comprising a base adapted to rest on the glass, said base having a vertical upstanding 10 pivot, a bearing member mounted for complete rotation on said pivot, and a cutter head carrier provided with a cutter head at one extremity and a counterbalancing weight at the opposite extremity, having pivotal 15 connection with the bearing member on the

same side of the pivot as the counterbalancing weight.

6. A portable device for cutting glass disks comprising a base adapted to rest on the glass, said base having a vertical upstanding pivot, a bearing member mounted for complete rotation on said pivot, and a cutter head carrier provided with a cutter head at one extremity and a counterbalancing weight at the opposite extremity, having pivotal 20 connection with the bearing member on the opposite side of the vertical pivot to the side from which the cutter head is arranged. 25

CARL F. DOERR.
